UNITED STATES PATENT OFFICE.

HOLMES MARSHALL, OF CLEVELAND HEIGHTS, OHIO.

SAFETY-DEPOSIT BOX.

Application filed December 19, 1922. Serial No. 607,768.

This invention is directed to improvements in a locking or sealing system for safety deposit receptacles, such as I have disclosed in my prior Patent No. 1,487,001, issued November 28th, 1922.

The general object of the present invention is to provide a system of the character referred to which is greatly simplified while being secure and more certain in preventing the surreptitious opening of the receptacles or the tampering with or the disturbing of the contents thereof.

More specifically, my present invention contemplates the use of a novel data slip or identification card which may be acted upon by means co-operating with the lid or cover of the box whereby ineradicable indicia or marks, such as perforations or stampings corresponding to the number 15 pertaining to the box, may be automatically placed upon the card when the box is closed.

An additional object of my invention is the provision of a deposit box and mechanism contained therein for fulfilling the foregoing objects while retaining the feature disclosed in my patent referred to, of positioning the card within the box in such manner as to display the patron's signature, through an opening formed in the front of the box and which may be acted upon by means co-operating with the cover of the box whereby the card is mutilated adjacent the owner's signature.

A further object is to provide such means in a simple and compact form which may occupy a minimum amount of space within a deposit box. A further object is the provision of all of the foregoing means in a system which will obviate the necessity for 40 individual keys by either the vault custodians or patrons.

An additional object is the provision of a novel lining for such a deposit box which is directed to the prevention of tampering with the box contents by the possible bending or distorting of the box cover without causing the foregoing described means to function in marking the card.

My invention is hereinafter more fully described and is illustrated in the accompanying drawings. The essential characteristics are summarized in the claims.

In the drawings, Fig. 1 is a perspective view of a safety deposit box; Fig. 2 is a longitudinal cross section taken through the front end of the box showing the card per-

forating means in a normal co-operative position; Fig. 3 is a similar view illustrating the manner of actuating the card perforating means when the lid or cover of the box 60 is raised from closed position; Fig. 4 is a cross sectional plan view taken substantially along the lines 4—4 of Fig. 2; Fig. 5 is a fragmentary plan view of the front portion of the deposit box; Fig. 6 is a view of 65 the identification card; Fig. 7 is a fragmentary cross sectional view taken through one of the front corners of the box showing other card perforating means; Fig. 8 is a perspective view of a card perforating member. 70

My present system contemplates the elimination of the necessity for a mechanical lock, such as is now in use upon deposit boxes, the responsibility for the safe keeping of the contents of the unlocked boxes being carried by the institution which leases the boxes to the patrons. In general, the system merely requires the use of a card which is tendered to the patron by the custodian of the vault chamber before access to the box is 80 permitted. The card is signed by the patron in the presence of the custodian who thereupon stamps the time and date upon the card, and thereafter the custodian accompanies the patron to the particular designated box whereupon the custodian compares the signature of the new card with the signature on the card positioned within the box. Upon a satisfactory comparison, the patron receives the box and the new card. Before 85 the patron closes the box for re-depositing in the vault, the old card, which was automatically marked upon the opening of the box by the patron, is withdrawn and the new card is then inserted. Upon leaving 90 the vault the patron tenders the old card to the custodian whereupon it may be stamped with the time and date and filed away for future reference.

Describing the various elements comprising the means by which I carry out this system by the use of reference characters in Fig. 1, I show a suitable safety deposit box 10 provided with a hinged cover 11 which may have downwardly extending side 105 flanges at 12 closely engaging the side walls 13 of the box. I provide an aperture 14 formed in the front wall 15 of the box whereby a signature on a card positioned within the box in a manner to be presently 110 set forth, will be displayed.

Disposed inside of this front wall of the

2

box, I position a transparent panel 16 suitably apertured as indicated at 17 to permit the projection of the cutting edges 18 of a perforating member 19, swingably mounted 5 within the box adjacent the inner surface of the box. The swingable member 19 is supported upon lugs 20 upset from the bottom wall of the box-like frame 21 positioned within the box immediately adjacent the inner face of the card. This frame structure 10 may be secured to the front wall of the box by any suitable means such as shouldered bolt members 23. Disposed between the front wall 21^a of the frame 21 and the front 15 wall 15 of the box, I provide a flat partition strip 22 having an outwardly extending flange 22^a abutting the end wall 15 of the box, the flange affording support for the transparent panel 16. As shown in Fig. 4, 20 the panel and the flange member 22, as well as the wall 21^a of the frame member 20, are secured to the box structure by the bolts 23. There are, however, spacing members 14^a disposed between the wall 21^a and the member 22 whereby sufficient space is provided 25 therebetween for the reception of a card C. The rear wall 21^b of the frame 21 may be provided with openings 21^c to permit access to the nuts 25 engaging the inner ends of the 30 bolts 23.

To simplify the perforating mechanism, the perforating member 19 may have the form shown in Figs. 2, 3 and 8. An upwardly curved portion 26 is adapted to be 35 acted upon by a suitably mounted cam member 27 carried by a bifurcated bracket 28 secured to the cover of the box and positioned on the cover to pass through a suitable opening 21^d formed in the top wall of the frame 40 21. The bracket member 28 carries the cam member 27 between bifurcated ends 28^a, there being a connecting web 28^b which affords a shoulder for the abutment of the cam member 27 in the manner shown in Fig. 3, 45 when the cam member is acting upon the perforating member 19 during the opening movement of the lid 11.

To maintain the perforating member normally out of contact with the card, a spring 50 member 31 may be mounted upon a pin 30 comprising a hinged connection between the lugs 19^a of the member 19 and the upwardly extending lugs 20 upset from the bottom wall of the frame member 21. One end of 55 the spring may therefore extend to engage the perforating member 19 to maintain it in a substantially retracting position as illustrated in Fig. 2, while the other end engages the front wall of the frame member 21, the lower end 19^b being formed to abut the bottom wall of the frame 21.

The action of this perforating mechanism is as follows:—

When the cover is swung into closed position, the cam member 27 swings out of abut-

ting relation with the web 28^b of its bracket 28, due to the engagement of the cam member 27 with the upper edge of the curved portion 26 of the perforating member 19; the cam member 27 during this movement 70 being in a substantially vertical position. As the cover is brought to closing position, however, the end 27^a of the cam member engages the bottom wall of the frame member 21 and thereby causes the positioning of the 75 cam member, as shown in Fig. 2 with the front end thereof disposed beneath the projection 26 of the perforating member. Upon a raising of the lid to gain access to the box contents, the cam member 27 engages 80 the projection 26 and causes a quick canting or swinging movement thereof, thus causing the cutting edges or teeth 18 to pass through the aperture 12^f formed in the front wall 85 of the member 21 in alignment with the aperture 17, etc., and the card is perforated in the manner indicated at 32, Fig. 6.

To afford ready insertion of the card in the space provided therefor, while at the same time proportioning the card to have sufficient width whereby the card cannot be shifted out of position when once in the box, I form notches in the sides thereof, as indicated at 33, and a projecting corner 33^a whereby the lower portion of the card may 95 occupy the entire transverse length of the card space and abut the spacing members 24. The card when being inserted is first tucked to the left with the corner 33^a disposed beneath the left bolt 23 and then shifted to 100 the right to engage the other bolt 23.

The card is provided with a perforation 34 corresponding to the general contour of the opening 21^d formed in the top wall of the frame member 21 whereby the upper portion of the card may be bent or folded along the dot and dash line as indicated at 35, Fig. 6, whence that portion of the card may lie horizontally in contact with the upper wall of the frame member 21 and be supported 110 thereby. Hence when the box is closed, the bracket 28 will pass through the card opening 34 and prevent shifting of the card.

To further insure the accuracy of the system, I provide a number chart upon the upper portion of the card, as shown in Fig. 6, which may occupy the available space to the left of the opening 34 while that portion of the card to the right provides space for the placing of the time stamp by the custodian, 115 as hereinbefore described. The object of the numerical chart is to conceal the designated number of the deposit box from any other patron, while at the same time, I provide means, preferably upwardly extending 120 points 37, in the top wall 21^d of the frame member 21, whereby the closing of the lid will effect a perforation of the card in the manner shown at 36 in Fig. 6.

The chart may be printed upon the card 125

for instance with vertical and horizontally extending lines designated by numerals along the left margin, whereby any combination of numbers may be obtained over a wide range. As illustrated, the particular perforation may be determined by reading the designated marginal figures. It will readily be seen that a large number of permutations may be obtained by the use of 10 such a chart.

To insure the perforating action of the points 37, I may provide a resilient pad 38 upon the inner surface of the cover member 11 to firmly press the card against the points 15 to effect the perforation thereof.

To prevent tampering with the contents of the box by distorting or bending the lid or cover 11, I provide an inner loosely positioned lining 40 formed of heavy cardboard 20 or a suitable fabric which may be folded in the manner illustrated. This lining may overlap as indicated at 41 to prevent the removal for instance, of valuable papers by insertion of a tool or wire, or a knife under 25 the flange 12 of the cover while maintaining the front of the cover in closed relation to prevent perforation of the card. The lining 40 may extend within the box the full length of the cover and rearwardly of the hinge construction 42 connecting the cover 30 to the box. The forward end 43^a of the top flap may extend over the horizontally disposed portion of the identification card which may be perforated as indicated at 35 Fig. 5 to permit free movement of the bracket 28 when closing or opening the box. This arrangement of having the member 28 extend through an opening in the top flap of the lining affords a simple means of 40 preventing a shifting of the lining.

It will be seen that from the foregoing description, I provide a system of checking the visits of the patrons of an institution renting or leasing safety deposit boxes which 45 affords a double check on the accurate identification of the patrons before access to any designated safety deposit box is permitted, while at the same time, eliminating the use of either a single or double key system which 50 is frequently annoying to the patron inasmuch as keys sometimes are forgotten or have become misplaced when a visit to the deposit box is contemplated. Moreover my system is very much cheaper than the individually locked compartments now in use, and in addition thereto an accurate check of 55 the patron's visits may be kept by stamping the cards as indicated at C¹ and C² and filing them away for future reference.

60 I claim:

1. In a deposit box having a cover, a data card supported in the box and marking means within the box cooperating with the cover, to select a certain group of numbers on the 65 card by marking the card.

2. In a safety deposit box having a cover, an identification card positioned behind the forward wall of the box, means behind the card coacting with the cover to mutilate the slip upon raising the cover, said means comprising a cantable member resiliently maintained out of contact with the card, a cam member pivotally mounted on the cover and coacting with the cantable member to mutilate the card. 70

3. A safety deposit box having a cover and perforating means rigidly mounted within the box for impressing certain indicia thereon corresponding to the number of the box upon a closing movement of the 75 cover, said means comprising perforating members arranged in predetermined relations relative to the position of the card within the box, whereby the perforations effected upon the card will be in predetermined positions on a number chart printed upon a card. 80

4. The combination with a safety deposit box, of means for carrying a data card thereon provided with a numerical chart, and means 85 operated automatically consequent upon opening and closing the box to punch the card and thus indicate numerals, the punching means being fixed for any particular box.

5. A safety deposit box having a movable 90 cover, a data card having a numeral chart, means for carrying the data card on the box, and punches carried in fixed relation within the box and adapted to punch the chart to indicate numerals corresponding to the number 100 of the box.

6. In a safety deposit system comprising a deposit box having a cover and carrying therein a card having a signature of the lessor of the box thereon, interiorly disposed 105 means carried by the box whereby the cover cannot be closed without impressing certain marks completing indicia upon the card corresponding to the number of the box.

7. In a deposit box having a cover, a data 110 slip supported in the box, and perforating means within said box co-operating with the cover whereby movement of the cover may cause the formation of punched openings in prearranged order which indicate numbers 115 on the card corresponding to the number of the deposit box.

8. In a deposit box having a cover, a data card supported in the box, and perforating members within the box adapted to effect 120 punching marks on the card indicating the number of the box when said box is opened and closed.

9. In a safety deposit box, means for retaining a data card adjacent the inside front 125 wall of the box, a defacing member for mutilating the card inside of the box, means carried by the cover for actuating said defacing member, and means also carried by the cover for preventing displacement of the card. 130

10. In a safety deposit box system, comprising a deposit box having a cover and carrying therein a card having the signature of the lessor thereon, interiorly disposed 5 means whereby the cover cannot be closed without impressing certain marks upon the card which indicate the number of the box,

and means active when the box is closed for preventing displacement of the card within the box.

10

In testimony whereof, I hereunto affix my signature.

HOLMES MARSHALL.
